UNITED STATES PATENT OFFICE.

SOLOMON L. VAN METER, JR., OF LEXINGTON, KENTUCKY.

SAFETY DEVICE FOR AERONAUTICAL MACHINES.

1,386,815.

Specification of Letters Patent. Patented Aug. 9, 1921.

Application filed June 28, 1919. Serial No. 307,362.

To all whom it may concern:

Be it known that I, SOLOMON L. VAN METER, Jr., a citizen of the United States, residing at Lexington, in the county of Fayette and State of Kentucky, have invented certain new and useful Improvements in Safety Devices for Aeronautical Machines, of which the following is a specification, reference being had therein to the accompanying drawing.

This invention relates to safety devices for aeronautical machines whereby the occupants of the machines can make their descent in safety to the ground in event of accidents or other causes which might make descent in the machines impossible or dangerous.

Greater degree of safety is now generally recognized as fundamentally essential in the future of aeronautics. The subject is receiving the careful attention of inventors, and interests generally engaged in the manufacture and commercialization of various types of flying machines, particularly of aeroplanes. The various Governments are also giving the subject most careful attention and are coöoperating in various ways to work out an effective solution of the problem.

In this connection my present invention is preceded by two earlier inventions relating to the same purpose but consisting of a different arrangement of mechanical devices. These earlier inventions comprise the subject matter of Patents No. 1,192,479 and No. 1,192,480, issued to me July 25, 1916.

An object of my present invention is to provide aeroplanes with one or more parachutes of any preferred construction to be connected to the bodies of the occupants of the machines or the machines themselves in a suitable manner and adapted to be suitably mounted on or in the aeroplane, which may be cast off or projected from the aeroplane by any suitable force controlled by the aviator or other occupant of the machine.

The means for casting off the parachutes may consist of any suitable mechanical devices, such as compressed springs, or compressed air or rush of air due to ship falling, manually controlled by an occupant of the machine, or controlled by suitable connections whereby the parachutes will be cast off without any conscious act. Such means may consist of automatic mechanism operated by an occupant jumping from the machine, or by the action of the air in case of

a falling machine. As here shown, however, the mechanism for casting off the parachute is controlled manually.

An object of the invention is to provide a parachute and suitable means for controlling the same which will be effective for its purposes and in which failure of operation under all conditions will be reduced to a negligible degree.

A further object of my invention is to provide improved shock absorbing means between the parachute and the occupant of the aeroplane whereby the force of the shock when the parachute is cast off will be absorbed sufficiently to avoid injury to the occupant.

A further object of the invention is to provide safety devices in connection with the seats and body structure of the aeroplane whereby an occupant of the machine may be removed therefrom by the parachute without sustaining bodily injuries.

It is also an object of my invention to provide an improved cast-off harness to be worn by an occupant of the aeroplane whereby he may be releasably secured to the seat of the machine and to the parachute and which may readily be released and cast off when the ground is reached to prevent injury to the occupant by being dragged over the ground by the parachute.

These main objects of my invention are realized by an improved construction of the various devices which are comprised in the apparatus, and by a novel arrangement of the devices whereby the functioning thereof relative to each other and to the apparatus as a whole is made dependable, the possibility of failure of the device to function properly under all circumstances being reduced to a minimum.

While the construction here shown is a preferred form as to the underlying principles of the invention, the details of construction and mechanical arrangement are to some extent conventional and are shown for illustration purposes only, as it will be understood that the details may be widely varied without departing from the principles and spirit of the invention.

In the accompanying drawings,

Figure 1 is a perspective view of the aeroplane in flight and showing the parachute container as first cast off from the machine;

Fig. 2 is a side elevation of an aeroplane on the ground equipped with my safety de-

vices, and having the door removed to the space in which the parachute and casting-off mechanism are contained;

Fig. 3 is a perspective view showing the 5 aeroplane falling and the second stage of operation, the parachute having been released from the container and opened to the air, the aviator having been removed from the machine;

10 Fig. 4 is a side elevation, with parts broken away, of a detail of the aeroplane showing the manner of mounting the parachute container and cast-off mechanism in the aeroplane, the safety arrangement in 15 connection with the seat and the connections for releasing the parachute;

Fig. 5 is an enlarged side elevation, partly in section, of the parachute container, showing the manner of folding the parachute and 20 parachute spreaders within the container;

Figs. 6 and 7 are front and rear views respectively of the harness as worn by the aviator whereby he is connected to the parachute and to the seat of the aeroplane;

25 Fig. 8 is a detail view of the guide used to protect the aviator from injury as he is removed from the machine;

Fig. 9 is a detail view of the mechanism for releasing the aviator from the seat;

30 Fig. 10 is a detail of the mechanism for releasing the parachute cast-off mechanism;

Fig. 11 is a detail of the mechanism for releasing the parachute from its container;

Fig. 12 is a detail view of the parachute 35 removed from the container and showing the arrangement of the spring steel loops for opening the parachute to the air when it is cast off from the aeroplane;

Fig. 13 is a detail side elevation, partly in 40 section, of a preferred arrangement of the seat construction and combination cover for the parachute compartment and guide way for the aviator when he is removed from the machine;

45 Fig. 14 is a detail view of one form of construction for using compressed air for casting-off the parachute;

Fig. 15 is a detail perspective view in 50 cross section taken on the line 15—15 of Fig. 13;

Fig. 16 is a detail plan view of the mechanism for locking and releasing the "turtle back" of the aeroplane.

As here shown my invention may be applied to any of the well known types of aeroplanes or other flying machines, requiring only modifications of details of construction and arrangement to adapt the same to the different types of machines.

60 As shown in the drawings, a suitable space is provided in the fuselage of the aeroplane for the parachute container and the cast-off mechanism.

As best shown in Fig. 4 the parachute 65 space is located at the rear of the pilot's

seat, substantially at the center of the fuselage. The fuselage is preferably provided with a side opening 1 and a door 2 whereby the parachute mechanism is readily accessible. An aperture 3 is provided in the top 70 cover or back of the fuselage through which the parachute container is projected when cast off from the machine. The aperture is preferably covered with a piece of cloth or any suitable material having perforated 75 seams and a coat of aeroplane dope applied thereto, thus serving to prevent ingress of dust and moisture to the compartment, and being readily yieldable to the force exerted thereon when the container is 80 ejected from the machine.

As best shown in Fig. 5 of the drawings the parachute container consists of a cylindrical, metal casing, a light metal such as aluminum being preferably used, having a 85 conical-shaped top 4, whereby to minimize resistance of the air when the container is cast off; and having its cylindrical wall formed of a plurality of slats 5, hinged at their upper ends adjacent the conical top 4, 90 as at 6, and having their lower ends confined within a bottom plate 7, whereby when the bottom is removed the hinged slats, due to the pressure thereon from within, will open outwardly to release the parachute, as 95 best shown in a detail of Fig. 3.

The bottom 7 consists of an integral plate having a central base portion 8 upon which the parachute parts rest when packed in the container, a peripheral flange 9 and an annular depression 10 inwardly adjacent the flange within which the free ends of the slats 5 are confined, when the container is closed. The under side of the bottom plate is depressed and has slidably secured to the 100 plate therein oppositely disposed spring plunger bolts 11 which engage at their outer ends detents 12 formed in two opposite slats 5. The plungers are supported in suitable bearings on the bottom plate and rest with 105 their inner ends against a locking plate 14 which is mounted on the plate 7 and is operable to release the plungers, and adapted to normally hold the same outwardly projected in engagement with the slats 5. When the plate 14 is operated its inner end moves out 110 of contact with the plungers which are then projected inwardly by the compression springs 15, thus releasing the plungers from the slats 5, and permitting the bottom plate 120 to fall free of the container, and the slats 5 to swing outwardly to release the parachute.

To facilitate releasing of the parachute from the container a compression spring 16, confined in a cover 17 is preferably employed 125 within the cone 4, the parachute being compressed against the spring is thrown outwardly with the expansion of the spring when the bottom plate of the container is released. To further facilitate delivery of 130

the parachute the cone-shaped end of the container is provided with air vanes or fins 4^a which are acted upon by the air when the container is projected from the machine in a 5 manner which causes the container more readily to assume a streamline relation to the machine and therefore directly in line for the withdrawal and expansion of the 10 parachute when the connecting line is drawn taut.

The plate 23 upon which the parachute container rests is connected to the seat and aviator releasing mechanism by a cable 19 which is preferably inclosed in a tube 19^a 15 to prevent accidental displacement thereof. The cable is preferably operable over a small roller 20^a secured to the stationary telescopic casing 21 and may be connected to the plate 23 in any suitable manner.

20 The parachute is connected to a harness worn by the aviator in any suitable manner by a connecting rope or cable 18, a portion of the rope being coiled and confined preferably within the parachute container 25 to provide for suitable distance between the parachute and the aviator when the parachute is cast off.

The parachute cast-off mechanism, as here shown, consists of a compression spring 20 30 confined within a telescopic casing 21 and 22, the lower section 21 of the casing being secured in any suitable manner on the frame of the fuselage, and the upper section 22 being movable with the spring in the upward projection thereof. The casings 21 35 and 22 have large openings 21^a and 22^a which serve to prevent the formation of a vacuum therein. The plate 23 is secured to the upper end of the casing 22 and acts 40 as a support for the parachute container and as a seat for the upper end of the spring 20.

In normal position the spring 20 is compressed and the casings 21 and 22 are in 45 the relation shown in Fig. 4, the parts being held in normal relation by a stirrup-shaped locking member 24 which is supported in the plate 23 and has its projecting ends 25 extending through the base in the bottom 50 of the fuselage upon which the cast-off mechanism is mounted. The projecting ends of the stirrup are notched as at 26 and are engaged in locked position by oppositely disposed latch plates 27, the inner ends of 55 the latch plates being supported by a vertically pivoted lever 28 which has its free end held in raised position by a horizontally pivoted latch 29 operable from the seat of the aeroplane by a rope 30. The operation 60 of the casting-off mechanism will presently be described in connection with the operation of the safety devices as a whole.

As shown in Figs. 6 and 7 the harness worn by the aviator as contemplated in my 65 invention may consist of the usual body belt

31 having a quick releasing clasp 32. Connected to the body belt by loop straps 33 are leg belts 34. A metal plate 35 suitably covered and padded is secured to the body belt at the back; shoulder straps 36 connect 70 ed to the plate and looped to the body belt in front aid in supporting the plate in right positions.

Coiled on the plate 35 and secured thereto by shock resisting bindings 37 is an elastic 75 cable 18^a which forms the first section of the connecting cable 18^d between the aviator and the parachute and serves to reduce the force of the shock transmitted to the aviator when the parachute is cast off and opened to the 80 air. The shock resisting bindings 37 also act to further absorb the shock, the bindings releasing one after another as the connecting cable is drawn taut.

As shown in Fig. 9 the mechanism for 85 releasing the aviator from the seat consists of a suitable casting 39 secured to the under side of the seat and having formed at its opposite outer ends enlarged portions 40 which are apertured to receive downwardly projecting 90 apertured extensions 41 secured to the opposite sides of the seat, and apertured links 42 suspended from the harness worn by the aviator. The apertures in the extensions 41 and links 42 when in normal relation with 95 the parts 40 are substantially in alinement with the spring plungers 43 and are adapted to be engaged by the outer ends of the plungers, the aviator being thus securely held on the seat of the machine.

The plungers 43 are normally held outwardly in engagement with the extensions 41 and links 42 by a locking block 44 which is secured to a bolt 45 and mounted on the frame 39 between bearings 46 in which the bolt 45 is supported. When the locking block 44 is withdrawn out of contact with the plungers 43 the springs 47 act to retract the plungers out of engagement with the ears 41 and links 42, thus releasing the 110 aviator and permitting the back of the seat to swing rearwardly, as best shown in Fig. 8 of the drawings, the seat being pivotally connected in a suitable manner to permit of the tilting movement thereof.

To insure positive releasing of the plungers 43 from the seat connections 41 and belt connections 42 the plungers are mounted in open bearings or guides 48, which, when the locking block 44 is withdrawn, permit the 120 inner ends of the plungers to swing downwardly and the outer ends to be drawn upwardly until the projections 41 and links 42 slip free of the plungers. The cable 19 connects the releasing block 44 to the supporting plate 23 of the parachute cast-off mechanism as above described, the cable being connected to the block in any suitable manner. Thus, with the actuation of the cast-off mechanism, by drawing on the rope 30 the plate 23 will 125 130

be projected upwardly by the spring 20 and will act through the cable 19 to withdraw the block 44, thereby releasing the aviator from the machine and permitting the seat 5 to pivot rearwardly to accommodate the movement whereby the aviator is removed from the machine.

In the operation just described the releasing of the block 44 is readily accomplished 10 through the pull upon the rope 19 and the pressure of the spring near the bearing 46, which together are more than sufficient to overcome the pressure of the spring of the metal of which the bar 45 is composed.

15 Should however, it be desired to not use automatic means for this purpose, the releasing can be brought about manually, by the pilot from his chair. It will be observed in Fig. 4 that the rope 30 terminates at the seat in a 20 ring to which a smaller rope 30' is attached being fastened at its farther end to the lower end of the latch 31' pivotally mounted upon an angular piece 32' depending from the frame work. Now instead of relying upon 25 the automatic means, the operator may pull upon the rope 30' and thus swing this pivotally mounted latch 31' from its engagement with its notch in the end of the bar 45 whereupon the pressure of the spring near 30 the bearing 46 will be quite sufficient without a pull upon the rope 19, to bring about the actuation of the releasing mechanism.

As best shown in Fig. 8, an inclined guide-way 51 is provided at the rear of the seat 35 which serves to guide the body of the aviator as he is removed from the seat and to protect him from injury by striking the sides or projections of the machine. As above stated, when the aviator is released from the seat, 40 the back of the seat also is released and swings rearwardly to substantially the inclination of the guide-way 51, thus permitting the aviator to be more readily removed from the machine.

45 A detachable cover plate 52 is normally closed over the guide way 51 and is held in position by cords (not shown) or other suitable connections secured thereto which are released when the aviator is released from 50 the seat, thus permitting the cover plate 52 to fall free of the machine.

The arrangement shown in Fig. 14 of the drawings for operating the parachute cast-off mechanism by compressed air is for purposes of illustration only without reference to exact details of construction, as various forms of pneumatically operated devices may be employed for this purpose. As here shown, the arrangement consists of a suitable cylindrical casing 54 in which the parachute container is seated upon a piston 55 which works within the casing and normally forms the bottom thereof. The casing is further provided with an enlarged hollow 65 base 56 having an inner casing or tube 57

extending vertically through the center thereof and resting at its upper end against the piston 55. The piston has a stem 58 extending downwardly through the tube 57 by which it may be releasably secured in 70 any suitable manner, as here shown by notches 59 formed in the end of the piston stem, to the bottom of the base 56. The piston is further secured to the bottom by means of a slackened cable 60 which passes 75 through an aperture 61 at the juncture of the stem 58 with the piston, and is anchored at its opposite ends to the bottom of the casing. Thus it will be seen that the cable will act to limit the extent of upward movement of the piston.

Within the base 56 any suitable means may be provided for containing air under pressure, which when released will act with sufficient force to drive the piston upwardly, 85 thereby casting off the parachute in the manner herein described. As here shown, the means for providing the air pressure consist of an expansible circular tube 62 adapted to be inflated in the usual manner 90 through a valve 63. A portion of the tube when inflated rests against the piston 55 and, when the piston is released, expands into the open end of the casing 54, moving the piston upwardly until the tube blows 95 out by expansion; the released air then acting to drive the piston upwardly with sufficient force to cast off the parachute. To hasten the blow-out of the tube, sharpened projections 64 may be provided at the entrance to the casing 54 which will act to puncture the tube and release the air therein directly with the expansion of the tube beyond normal. The stem 58 may be released from the bottom of the casing in any suitable manner as in the other form of construction described.

To prevent the parachute container from falling through the aperture 3 when flying upside down, the outer spring casing 22 is provided with two apertures 22^b arranged diametrically opposite each other in the casing, each having a curved finger 22^c co-operating therewith. Cords 22^d secured at one end to the bottom plate 8 of the container 110 passing through the steel plate 23 are looped over the fingers 22^c at their opposite ends in a manner to be readily released with the upward movement of the parts when the cast-off mechanism is actuated, but acting normally to prevent displacement of the parachute container in event of flying the machine upside down.

To protect the parachute parts within the container from dust and moisture, the bottom plate 8 is preferably sealed with a cover of heavy paper 8^a treated with suitable aeroplane "dope" to make the same impervious to moisture. The paper covers all apertures in the plate leading into the interior of the 125 130

container, and is held in place on the plate by an expansion ring 8^c which fits into the flange of the plate.

The parachute spring expanders 18, as here shown, consist of surveyor's steel tape of plural strength,—about four-ply being found most satisfactory. When the parachute is confined within the container the loops of the springs are folded upwardly, as shown in Fig. 5. When the parachute is re-reased these loops spring outwardly and spread the parachute at its bottom to open it to the air. The springs are secured to the parachute by suitable clips 18^b which secure the springs releasably to a cord 18^c secured to the bottom edge of the parachute. When the parachute is opened the clips release the cord and the spring expanders fall free of the parachute.

In the preferred construction shown in Figs. 13 and 14, the underlying principle of construction and operation is essentially the same as in the construction above described. However, the details of arrangement and operation are radically different, the differences consisting essentially in the means for casting off the parachute and in guiding the occupant from the machine.

As best shown in Fig. 13 the "turtle-back" of the fuselage is formed of a tilting back 65 which extends well toward the rear of the fuselage and is hinged or pivoted to the frame thereof in any suitable manner, as at 66. The forward end of the back is provided with an auxiliary back 67 which is pivoted to the main back 65 as at 68. When the backs 65 and 67 are in normal position relative to the fuselage they may be held in place by any suitable locking mechanism, such as is shown in one form in Fig. 15 of the drawings, which is mounted in the back 65 in any suitable manner and consists of a cam plate 69 having cam slots 70 disposed on opposite sides of the center thereof and coöperating with lock bolts 71 operating through guides 72 and through the casing of both covers 65 and 67 and having their ends projecting through lock plates 73 which are secured to the opposite longerons 74. Thus both the backs 65 and 67 will be releasably held in normal position.

To release the backs the aviator draws on a rope 75 connected to a cam plate 69 by a lever 76, thus actuating the plate clockwise to withdraw the lock bolts 71 from the plates 73 and from the back 67. When the backs 65 and 67 are thus released, the action of the air on the back 67 will cause it to rise to a position substantially at right angles to the fuselage and to the back 65. Air pockets 77 of suitable shape and capacity are preferably provided at the forward end of the back 67 to cause the air to more readily lift the cover, or rather to start the lifting or opening movement thereof. With the be-

ginning of the opening of the back 67 lifting force due to the increasing air pressure will be exerted on the back 65 which will rise with a rapid movement to a position substantially parallel with the center line or stream line of the tail of the machine which is of modified construction, as shown in Fig. 13.

The force of contact of the back 65 with the fin 78 of the tail will act to cause the fin 75 to break through the fabric-covered back 65, when the same is operated to full-open position. To minimize breakage or other damage to the structure of the fuselage is provided with a longitudinal open space 79, extending substantially the entire length thereof, and having an elastic or shock absorbing element 80 of any suitable material interlaced between the vertical braces 81 whereby the force of contact will be broken.

The opening of the backs 65 and 67 may be accomplished entirely, as above described, by the action of the air, or, if desired, mechanical devices such as a spring 82, connected to the cover 65 by a cable 83 may be employed in connection with the action of the air to lift the backs. The spring may be normally compressed to any desired tension, thus acting to draw the cable 83 taut, and, when the covers are released, to exert its full force through the cable to aid in the raising of the cover 65.

In the form of construction here shown the parachute container 84 is secured to the back 65 and is carried upwardly therewith when the back is released to a position sufficiently above the air plane to permit of the proper releasing and expanding of the parachute. The container may be of any suitable construction whereby the parachute may be effectively delivered therefrom. As here shown the container is of the general construction shown in Fig. 5, but modified as to details. As shown in Fig. 13 the container is normally held in closed position by cords 85 secured to the bottom thereof and looped at their upper ends to receive holding fingers 86 secured to and operable by a cable 87 which is anchored in the bottom of the fuselage and extends upwardly to the top thereof and forwardly to its connections with the parachute container. When the container is carried upwardly with the back 65 the cable 87 will be drawn taut when the desired position to release the parachute is reached, and will act to withdraw the fingers 86 from the looped ends of the cords 85, thus permitting the bottom 88 and slats 89 to fall apart thereby to release the parachute.

An object of the preferred construction is to provide a longer guide way for the aviator as he is removed from the machine. To this end the guide way 90 is extended rearwardly in the fuselage substantially the

length of the turtle back 65, the guide being inclined upwardly at an easy angle from the rear of the seat to the top of the fuselage. When the back 65 is swung about its pivot 5 66 and reaches its operative position, the rear end of said back extends far enough to cause the aviator to clear the wires extending to the tail. This prevents the aviator from becoming entangled in these wires. 10 When the back 65 is in this position, it forms a continuation of the guide way 90.

As shown in Fig. 13, the guide 90 may be hinged at its rear end, as shown at 91, and connected at its front end to the base of the 15 seat, the front end of the guide, together with the seat and the aviator thereon, being adapted to move upwardly to a position in which the bottom of the guide is substantially parallel with the upper edge of the 20 fuselage, thus increasing the freedom of movement by which the aviator is set free of the machine by the parachute.

To cause the guide 90 and the seat to move upwardly with the lifting of the back 65 any 25 suitable leverage or lifting connection between the back and the guide may be provided. As here shown a rearward projection 92 of the back 65 may be employed which acts as a lever to engage the guide 30 forward of its pivotal connection in the fuselage, thus exerting lifting force thereon. Compression springs 93 mounted on the machine frame in tubes 93^a and engaging the seat on opposite sides thereof by cables 93^b 35 act further to lift the front end of the guide together with the seat and the aviator thereon to raised position.

In the modified construction here shown the seat back and sides are also mounted 40 pivotally in any suitable manner relative to the seat base, one preferred form being shown in detail in Fig. 9 of the drawings. Thus the back and sides of the seat when released may swing rearwardly until the 45 back is substantially in alignment with the inclined guide way 90 and out of the way of the aviator as he is lifted free of the machine. The seat releasing mechanism may be of the construction shown in Fig. 9, 50 or any other form suitable for the purposes.

To release the parachute and free himself of the machine the aviator draws on the rope 75, thus actuating the lock bolts 71 to release the backs 65 and 67, the latter lifting 55 first by the action of the air thereon, increases the resistance to the air and acts to lift the back 65, and with it the parachute container, which is opened and the parachute released therefrom by the releasing 60 cable 87 which acts to withdraw the releasing members 86 from the looped retaining cords 85. An extension 87^a of the cable 87, extends through a protecting tube 87^b and is connected to the seat releasing mechanism. 65 Thus with the releasing of the parachute

the aviator and back and sides of the seat are released from the bottom of the seat, the entire operation being properly timed to accomplish delivery of the parachute and aviator from the machine without interfering movements. 70

As above stated the details of construction and operation herein shown and described are intended for illustrative purposes only, to show the underlying principle of my 75 invention which consists in providing an aeroplane or other aeronautical machine with a parachute of suitable size and construction to be carried by the machine; to be released and cast-off the machine by any 80 suitable mechanism or force, and which, as opened to the air, acts to lift an occupant free of the machine, or to support the occupant in the air as the machine falls or travels away from him. To accomplish 85 these purposes any suitable force, such as air or mechanical devices or a combination of air and mechanical devices may be employed to perform the various operations of releasing the aviator and the parachute and 90 cast-off mechanism so that the aviator may be effectually released from the machine and safely conducted to the ground.

Having thus fully described my invention, what I claim as new and desire to secure by Letters Patent, is:— 95

1. In an aeronautical machine, the combination, a parachute carried by said machine, and ejector mechanism coöperating with the parachute, means for securing an 100 aviator in said machine, connections between the aviator and the parachute and means connecting the ejector mechanism to the securing means, whereby when said 105 ejector mechanism is actuated the parachute will be cast off and said mechanism will act to release said securing means and to free the aviator from said machine.

2. In an aeronautical machine, the combination, a parachute carried by said machine, and manually controlled ejector mechanism coöperating with the parachute, means for securing an aviator in said machine, connections between the aviator and the 110 parachute and means connecting the 115 ejector mechanism to the securing means, whereby when said ejector mechanism is actuated the parachute will be cast off and said mechanism will act to release said securing means and to free the aviator from said machine. 120

3. In an aeronautical machine, the combination, a container having a parachute therein, an ejector mechanism coöperating with said container, means for securing an 125 aviator in said machine, connections between the aviator and the parachute and means connecting the ejector mechanism to the securing means, whereby when said ejector mechanism is actuated the container will be 130

cast off, the securing means released thereby, and the parachute released from the container will act to remove the aviator from said machine.

5 4. In an aeronautical machine, the combination, a separable container normally closed and having a parachute disposed therein, an ejector mechanism coöperating with said container, means for securing an 10 aviator in said machine, connections between the aviator and the parachute and means connecting the ejector mechanism to the securing means, whereby when said ejector mechanism is actuated the container will be 15 cast off, the securing means released thereby and the parachute released from the container and opened to the air will act to remove the aviator from said machine.

5 5. In an aeronautical machine, the combination, a container having expandible walls normally confined to support a parachute therein, an ejector mechanism coöperating with said container, means for securing an aviator in said machine, connections 20 between the aviator and the parachute and means connecting the ejector mechanism to the securing means, whereby when said ejector mechanism is actuated the container will be cast off and the walls thereof expanded, the securing means will be released thereby, and the parachute released from the container will act to remove the aviator from said machine.

6 6. In an aeronautical machine, the combination, a container consisting of a cylindrical casing having an ejector spring compressed therein and a parachute disposed against the spring, an ejector mechanism coöperating with said container, means for 25 securing an aviator in said machine, and connections between the aviator and the parachute and means connecting the ejector mechanism to the securing means, whereby when said ejector mechanism is actuated the container will be cast off, the securing means released thereby, and the parachute released from the container by the expansion of said spring will act to remove the aviator from said machine.

50 7. In an aeronautical machine, the combination, a parachute carried by said machine and having an expander coöperating therewith, ejector mechanism coöperating with the parachute, means for securing an 55 aviator in said machine, connections between the aviator and the parachute and means connecting the ejector mechanism to the securing means, whereby when said ejector mechanism is actuated the securing means will be released thereby and the parachute will be cast off and actuated by said expander will act to remove the aviator from said machine.

8. In an aeronautical machine, the combination, a container having a collapsible

parachute and an expander therefor disposed therein, an ejector mechanism coöperating with said container, means for securing an aviator in said machine, connections between the aviator and the parachute 70 and means connecting the ejector mechanism to the securing means, whereby when said ejector mechanism is actuated the container will be cast off, the securing means will be actuated thereby to release the aviator, and 75 the parachute released from the container and actuated by said expander will act to remove the aviator from the machine.

9. In an aeronautical machine, the combination, a container having cylindrical 80 walls and a cone-shaped end forming a projectile and having a parachute disposed therein, fins on the exterior surface of the cone shaped end, an ejector mechanism coöperating with said container, means for 85 securing an aviator in said machine, connections between the aviator and the parachute and means connecting the ejector mechanism to the securing means, whereby when said ejector mechanism is actuated the container 90 will be cast off, the securing means released thereby, and the parachute released from the container will act to remove the aviator from said machine.

10. In an aeronautical machine, the combination, a parachute carried by said machine, ejector mechanism coöperating with the parachute, an inclined guide way coöperating with a seat, a detachable cover for the guide way and means to secure an aviator on 100 said seat, and connections between the aviator and the parachute and means connecting the ejector mechanism to the securing means, whereby when said ejector mechanism is actuated the parachute will be cast off, the 105 securing means will be released, and the parachute opened to the air will act to remove the aviator over said guide way from the machine.

11. In an aeronautical machine, the combination, a parachute carried by said machine, ejector mechanism coöperating with the parachute, a seat and cast-off harness worn by an aviator and means on said harness for securing the aviator to said seat, and connections between the parachute and means connecting the ejector mechanism to the securing means and said harness, whereby when said ejector mechanism is actuated the 115 parachute will be cast off and said mechanism will act to release said securing means and to free the aviator from said machine, and a quick release for said harness whereby the same may be cast off.

12. In an aeronautical machine, the combination, a parachute carried by said machine, ejector mechanism coöperating with the parachute, means for securing an aviator in said machine, elastic connections between the aviator and the parachute and means con- 125

necting the ejector mechanism to the securing means, whereby when said ejector mechanism is actuated the parachute will be cast off and said mechanism will act to release 5 said securing means and to free the aviator from said machine and whereby said elastic connections will act to absorb part of the shock transmitted therethrough.

13. In an aeronautical machine, the combination, a parachute carried by said machine, ejector mechanism coöperating with the parachute, means for securing an aviator in said machine, a plate and connections between the aviator and the parachute and 15 means connecting the ejector mechanism to the securing means, and a plurality of shock-absorbing fastenings securing said connections to said plate, whereby when said ejector mechanism is actuated the parachute will be 20 cast off and said mechanism will act to release said securing means and to free the aviator from said machine and whereby part of the shock transmitted through said connections will be absorbed by said fastenings.

14. In an aeronautical machine, the combination, a parachute carried by said machine, ejector mechanism coöperating with the parachute, means for securing an aviator in said machine, a plate and connections between the aviator and the parachute coiled 30 on said plate and a plurality of shock-absorbing fastenings securing said connections to said plate and means connecting the ejector mechanism to the securing means, 35 whereby when said ejector mechanism is actuated the parachute will be cast off and said mechanism will act to release said securing means and to free the aviator from said machine and whereby part of the shock 40 transmitted through said connections will be absorbed by said fastenings.

15. In an aeronautical machine, the combination, a parachute carried by said machine, ejector mechanism coöperating with the 45 parachute, means for securing an aviator in said machine, connections and a shock absorbing element between the aviator and the parachute and means connecting the ejector mechanism to the securing means, whereby 50 when said ejector mechanism is actuated the parachute will be cast off and said mecha-

nism will act to release said securing means and to free the aviator from said machine and whereby part of the shock transmitted through said connections will be absorbed by said fastenings. 55

16. In an aeronautical machine, the combination, a parachute carried by said machine, manually controlled ejector mechanism co-operating with the parachute, means for securing an aviator in said machine, connection between the aviator and the parachute and manually controlled means connecting the ejector mechanism to the securing means whereby when said ejector mechanism is 60 actuated the parachute will be cast off and the mechanism will act to release said securing means and to free the aviator from the machine. 65

17. In an aeronautical machine, the combination, a parachute carried by the machine, means for disengaging the parachute therefrom, a detachable seat, and releasing means therefor, harness worn by the aviator, links on said harness coöperating with said releasing means to hold the aviator to the seat, manually controlled ejector mechanism co-operating with the parachute, an inclined guideway coöperating with the seat and means connecting the ejector mechanism to 70 the means securing the aviator to his seat, whereby the aviator may eject the parachute and release himself from the machine. 75

18. In an aeronautical machine, the combination with a parachute carried by the machine, a detachable seat, means to secure an aviator in said seat and connections between the aviator and the seat and the parachute, manually controlled ejector mechanism co-operating with the parachute, a shock absorbing element between the aviator and the 80 parachute, an inclined guideway coöperating with the seat, and manually controlled means connecting the ejector mechanism to the securing means, whereby when the ejector 85 mechanism is actuated, the parachute will be cast off, the securing means released and the 90 parachute will remove the aviator from the machine. 95

In testimony whereof, I affix my signature. 100

SOLOMON L. VAN METER, JR.
